Primary Examiner — David G Muller*(74) Attorney, Agent, or Firm* — Rabin & Berdo, P.C.(57) **CLAIM**

The ornamental design for a hot stick, as shown and described.

DESCRIPTION

FIG. 1 is a front view of the hot stick;
 FIG. 2 is a rear view thereof;
 FIG. 3 is a top view thereof;
 FIG. 4 is a bottom view thereof;
 FIG. 5 is a right side view thereof;
 FIG. 6 is a left side view thereof;
 FIG. 7 is a reduced front view thereof;
 FIG. 8 is an enlarged left side view thereof;
 FIG. 9 is a reduced perspective view thereof;
 FIG. 10 is an enlarged view of cross-sectional surface 10-10 in FIG. 7; and,
 FIG. 11 is an enlarged view of cross-sectional surface 11-11 in FIG. 9.
 The broken lines illustrate unclaimed subject matter and form no part of the claimed invention.
